RIGID WELDED FRAME

Hugo Eckart and James E. McClellan,
Los Angeles, Calif.

Application June 21, 1940, Serial No. 341,700

2 Claims. (Cl. 189—36)

This invention has reference to structural frames, its particular objective being the provision of a rigid welded knee structure which is simple in design and construction, slightly in appearance and occupying a minimum space, and fully capable of taking the maximum moments imposed.

The invention is useful wherever the junctions of structural members are subjected to force moments. Its particularly typical use however is at the knees or apex of structural arch and similar frames, and so the invention will be described typically in such uses, but without limitation thereto. The features and characteristics of the invention will best be understood from the following detailed description of typical forms, referring for that purpose to the accompanying drawing in which:

Fig. 1 is a fragmentary elevation showing the application of the invention to a typical structural arch knee;

Fig. 2 shows the parts of Fig. 1 disassembled; Fig. 3 is a similar view showing application of the invention to the knee and apex of a "saw-tooth" structural arch;

Fig. 4 is a section on line 4—4 of Fig. 1; and Fig. 5 is a section on line 5—5 of Fig. 1.

In the drawing a column 10 is shown, and one beam member 11. Typically these may be a column and one beam member of a structural arch common in steel framed buildings; and typically these members are of I or H section. As such, they have webs 12 and 13 and flanges 14 and 15.

At the knee joint of members 10 and 11 both are cut back to remove their flanges. At a distance from their ends depending on the radius desired for the inserted gusset plate, the inner flanges of the column and beam are cut to present preferably square shoulders 16, which shoulders preferably also extend a short distance into the webs 12 and 13 as shown. Another cut is made, at 17 in the column and 18 in the beam, parallel to the length of those members and extending from their ends to the bases of the square shoulders 16. The members are thus recessed along their inner sides at their joining ends and the square shoulders 16 are presented at the ends of the recesses.

The two directly joining ends of the column and beam may be joined in any suitable manner. They are preferably shown as having the cut edge of one (as 18 of beam 13) overlapping and welded to the end of the other. For that purpose, as here shown, the end of the column is

cut at an angle as at 19 so as to abut flatly against the cut edge 18 of the beam flange; and the two abutting edges are welded, as indicated at 20 in Fig. 1. The outer flange 14a of column 12 may be continued upwardly across the end of beam 11 by flange extension 21 which may be welded to the column flange 14a at 22 and to the beam flange 14a at 23.

A gusset plate 30, roughly of triangular shape, is inserted in the angle between the beam and column, extending between the square-shoulders 16 and filling the recesses which have been cut out of the beam and column. For a structure such as shown in Figs. 1 and 2 the gusset plate 30 has a vertical edge 31 adapted to abut the vertical cut edge 17 of the column web, and a sloping edge 32 adapted to abut the cut edge 18 of beam web 13. The ends of the triangular-shaped gusset plate are defined by end surfaces 33 which abut the two square-shoulder surfaces 16 of the beam and column. When finally set up, as shown in Fig. 1, the abutting edges 31 and 17 are welded, as indicated at 34 in Fig. 1, and the abutting edges 32 and 18 are welded as indicated at 35 in that figure. And the abutting square-shouldered surfaces 33 and 16 are also welded as indicated at 36 in Fig. 1.

The otherwise free edge of gusset plate 30, indicated at 40 in Fig. 2, is preferably curved, and in the preferred design this curved edge 40 is preferably tangent to the external surfaces of flanges 14 and 15 of the column and beam. The curved edge of plate 30 is provided with a similarly curved flange 41 which is welded to plate 30 by the weld indicated at 42. Flange 41 may have its ends flush with the plate ends 33, and if the curved plate edge 40 is then designed to be recessed beyond the external surfaces of flanges 14 and 15, the ends of flanges 41 will abut the cut shouldered ends of flanges 14 and 15 and may be welded thereto. But it is preferred to make the structure as shown in the drawing, with the curved plate edge 40 tangent to the surfaces of flanges 14 and 15, and to extend the gusset flange 41 by extensions 41a which overlie flanges 14 and 15 and are welded to those flanges in any suitable manner. They are for instance shown as being welded around their end edges, as indicated at 44 in Figs. 4 and 5. Thus welded, the gusset flange 41 forms a connection continuation of flanges 14 and 15, capable of transmitting either tension or compression between the column and beam flanges.

The whole structure when finally set up and welded as shown in Fig. 1 forms an extremely

simple and exceptionally strong structure for the purposes which have been indicated. The size of the inserted gusset, and the radius of curvature of its curved edge and of flange 41, will depend upon purely engineering considerations of the stresses involved. But for any given size and design, the structure which we have here described is exceptionally strong and rigid because it forms a virtually integral connection between the beam and column and between the beam and column flanges, and because of the thrust taking abilities of the square thrust shoulders at 16, 33.

Fig. 3 shows the typical adaptation of our structure to a frame structure of the "saw-tooth" type. A column 12 is the same as that described in connection with Fig. 1, as is also the gusset plate 30 and its curved flange 41. Instead of overlapping the beam 11a over the top end of column 12, the inclined strut 12b has its lower end set upon the upper end of column 12, and against the end of beam 11a, and welded thereto as shown at 50. In the design as here shown, the angle included between column 12 and strut 12b is rather near a straight angle and therefore may not need the insertion of the gusset plate; but, if desired, the gusset plate structure may be inserted in that angle in the same general manner as inserted in the other angles here described.

The upper part of Fig. 3 shows the upper end of inclined beam 11b, which is a duplicate of the beam 11a whose lower end is shown in the lower part of Fig. 2. The juncture of the upper end of 30 11b and the upper end of inclined strut 12b is shown as being the same as that described in connection with Fig. 1, and thus involves the same gusset plate 30 with its flange 41, and the same relationships and weldings as described in connection with Fig. 1.

We claim:

1. A structure including two webbed and flanged structural members meeting and joined together at an angle with their webs in a common plane and with their inner flanged edges

defining an included angle of less than 180°, the two members being recessed along their inner angularly disposed edges, their recesses beginning at the meeting point of the two webs and the ends of their recesses being defined by substantially square thrust shoulders at the termini of their flanges and the sides of their recesses being defined by web edges substantially parallel to their lengths, a gusset plate having side edges fitting against and welded to said recess web edges, having end thrust shoulders substantially square to the side edges and fitting against and welded to the thrust shoulders which define the ends of the recesses, and the gusset plate having a curved flange welded thereto, forming a continuous connection between the flanges of the members and welded thereto.

2. A structure including two webbed and flanged structural members meeting and joined together at an angle with their webs in a common plane and with their inner flanged edges defining an included angle of less than 180°, the two members being recessed along their inner angularly disposed edges, their recesses beginning at the meeting point of the two webs and the ends of their recesses being defined by substantially square thrust shoulders at the termini of their flanges and the sides of their recesses being defined by web edges substantially parallel to their lengths, a gusset plate having side edges fitting against and welded to said recess web edges, having end thrust shoulders substantially square to the side edges and fitting against and welded to the thrust shoulders which define the ends of the recesses, the gusset plate having a concave edge which is substantially tangent with the inner surfaces of the member flanges, and a curved gusset flange extending along the curved plate edge, welded thereto, extending beyond the ends of the curved plate edge, overlapping the member flanges and welded thereto.
